BERNARD F. ROEHRIG, OF SAN DIEGO, CALIFORNIA, ASSIGNOR TO GEORGE REICHART, OF SAN DIEGO, CALIFORNIA.

KEROSENE INCANDESCENT LAMP.

No. 916,889.

Specification of Letters Patent. Patented March 30, 1909.

Application filed October 26, 1908. Serial No. 459,599.

To all whom it may concern:

Be it known that I, BERNARD F. ROEHRIG, citizen of the United States, residing at San Diego, in the county of San Diego and State of California, have invented certain new and useful Improvements in Kerosene Incandescent Lamps; and I do hereby declare the following to be a full, clear, and exact description of the invention, such as will enable others skilled in the art to which it appertains to make and use the same.

This invention relates to kerosene incandescent lamps. It is desirable in devices of this character to have the mantle centrally supported. It has been found that where the mantles are supported from the side, the rods or wires supporting them lie so close to the chimney that they tend to crack the chimney when they become highly heated. It is also desirable to have the chimney and mantle removable together from the burner. These mantles are very fragile, and in the devices of this character where it is necessary to separately remove the mantle, said mantles are frequently broken.

It is the object of the present invention to provide improved and economical means for accomplishing the foregoing objects.

It is a further object of the invention to provide means for spacing the outer wick tube hereinafter described from the interior of the sleeve from which the mantle is supported. The spacing of the wick tube from this sleeve provides a passage through said sleeve for the air which supports combustion and it has been found that if means are not provided for preventing it, the chimney is sometimes placed on the lamp in such manner that the outer wick tube is not exactly concentric with the sleeve that surrounds it. This of course gives an unequal flow of air and produces a ragged flame.

In carrying out my invention I do not wish to be understood that it should be confined to the details shown by the accompanying drawings. The inventive idea is broader than the particular embodiment herein presented and described, and embraces in construction and mechanism that which comes within the scope of the claims.

With these and other objects in view the invention comprises the novel features of construction and completion of parts herein-after described.

In the accompanying drawings, Figure 1 is a top view of the lamp with the chimney and mantle attached; Fig. 2 is a vertical section of the lamp cut in two, on lines 1—2; Fig. 3 is a front view of the lamp; Fig. 4 is a perspective of the burner detached and Fig. 5 is a detailed perspective view of the flame spreader and mantle support.

Similar letters refer to similar parts throughout the several views, in which—

A is the lamp-bowl; B is the inner wick-tube; C is the wick; D is the outer wick-tube, provided with flange D¹, carrying lugs D², holes E and plate F; on plate F is a detachable sleeve, G, containing openings, H, and the same is operated by band I with knob J; K is the receiver for the chimney, M; L are the pins attached to tube, K; N is the flame-spreader and mantle-rod support carrying rod N¹, said flame-spreader and mantle-rod support carrying arms O, provided with notches P, adapted to fit to the edge of rim G¹; R is the wick adjustment, which is provided with a collar having a projection T, said collar is also provided with set screw U; V is an angular iron made fast to the top of gear frame which acts as a stop for the wick; W is the detachable plug set in bowl A of the lamp for the purpose of filling the lamp.

Said lamp has a bowl of ordinary shape, and is provided with a central vertical tube which is attached to the bowl at the lower end, the upper end extending above the outer wick-tube and acting as the inner guide for an annular wick which fits around said tube, and is adapted to be raised and lowered thereon. On the outside of wick is a double detachable tube D, and on its upper inward portion is constructed a flange D¹, for the purpose of changing the current of air or oxygen that comes in contact with the flame, and on said flange are constructed lugs D², for the purpose of holding the sleeve C that operates the conical shaped flame-spreader and mantle-rod support in a perfect central position, so as to produce a perfect flame on all sides; the lower end of said tube D extends just below the top of bowl A and then flanges outward, and then upward, and upon the upward turn is formed a screw 100 which is adapted to fit another screw formed into the top portion of the said bowl, and the extending upward portion having openings

E for the purpose of allowing an air passage around its inward portion to keep same cool. At the top is attached an annular plate F that acts as a support for a detachable sleeve G, and prevents an unregulated amount of air from coming up between the outer wick tube and sleeve G. In the outward portion of sleeve G is a row of openings H and inside of said sleeve is a perforated movable band I, 10 made to correspond with said openings. J is a knob attached to the perforated movable band I, for the purpose of adjusting said openings in such a way as to allow the required amount of air to pass into the burner.

15 The upper part of sleeve G extends above the wick-tube and is so constructed as to form an inward projecting flange G¹, for the purpose of supporting the conical shaped flame-spreader and mantle - rod support. On 20 sleeve G, just above the openings in same, is attached a perforated tube K to receive the chimney M; pins L are attached to said tube K to prevent the chimney from going beyond said pins, and they also form a rest for said 25 chimney. Immediately above the inner wick-tube B is constructed a conical shaped flame-spreader and mantle-rod support N, and having an opening in its lower and central part, which is intended to receive the 30 mantle rod N¹, which supports the mantle in a perfect central position, and which allows the same to hang in a perfect position over the flame for the purpose of producing a perfectly adjusted flame from all sides; on the 35 upward edge of said conical shaped flame-spreader and mantle-rod support is constructed arms O, which project therefrom and are provided with notches P, adapted to fit to the rim G¹, allowing the central mantle- 40 support and conical shaped flame-spreader, together with the mantle, to be detached from sleeve G when lighting said lamp. In the operating appliance of the wick adjustment, the wick has an adjustable gear R, and 45 pinion attached, to be operated by a wheel made fast to said pinion in connection with an angular iron attachment V, which is made fast to the top part of the gear frame, and which is brought in contact with a projection T on collar S, which has a set screw U, and which allows said collar to be set at a given point on the vertical shaft, to prevent the wick from being turned too high, thus 50 adjusting the flame in a perfect manner.

55 Having thus described my invention, what I claim to be new, and desire to protect by Letters Patent, is:

1. A kerosene incandescent lamp comprising a bowl, an inner wick tube, an outer 60 wick tube having an out-turned flange at its upper end, a sleeve surrounding said wick tube and lugs formed at intervals upon the periphery of said flange and adapted to concentrically space the sleeve from the outer 65 wick tube.

2. A kerosene incandescent lamp comprising a bowl, an inner wick tube, an outer wick tube having an out-turned flange at its upper end, a sleeve surrounding said wick tube, lugs formed at intervals upon the periphery of said flange and adapted to concentrically space the sleeve from the outer wick tube, a centrally disposed flame spreader located concentrically above the inner wick tube, a centrally disposed mantle 70 support extending upwardly from said flame spreader, and spaced supporting members extending from the flame spreader to the upper edge of said sleeve.

3. A lamp comprising a bowl, a wick tube, 80 and a wick, a rack connected to said wick, a toothed member in mesh with said rack, a fixed member secured to the bowl, said fixed member having an overhanging portion, a member having an outstanding portion T 85 slidably disposed upon said rack, and a set screw U for binding said slideable member in a desired position upon said rack, the outstanding portion thereof being adapted to contact with the overhanging portion of the 90 fixed member to thereby limit the upward movement of the rack.

4. A kerosene incandescent lamp comprising a bowl, an inner wick tube, an outer wick tube having an out-turned flange at its 95 upper end, a sleeve surrounding said wick tube, lugs formed at intervals upon the periphery of said flange and adapted to concentrically space the sleeve from the outer wick tube, a centrally disposed flame 100 spreader located concentrically above the inner wick tube, a centrally disposed mantle support extending upwardly from said flame spreader, and spaced supporting members extending from the flame spreader to the 105 upper edge of said sleeve, there being a plurality of openings formed around the base of said sleeve.

5. A kerosene incandescent lamp comprising a bowl, an inner wick tube, an outer 110 wick tube having an out-turned flange at its upper end, a sleeve surrounding said wick tube, lugs formed at intervals upon the periphery of said flange and adapted to concentrically space the sleeve from the outer wick tube, a centrally disposed flame 115 spreader located concentrically above the inner wick tube, a centrally disposed mantle support extending upwardly from said flame spreader, spaced supporting members extending from the flame spreader to the upper edge of said sleeve, there being a plurality of openings formed around the base of said sleeve, and means for controlling the flow of air through said openings.

6. In a device of the character described, the combination with a bowl, of an inner wick tube and an outer wick tube having an out-turned flange around its upper end, the outer wick tube being bent outwardly, then 120 130

upwardly, and then inwardly from its lower end to form a horizontal flange, a flange F, a sleeve adapted to rest upon said flange, said sleeve being provided with chimney engaging members and there being lugs formed upon the out-turned flange of the outer wick tube adapted to concentrically space said sleeve from said wick tube, a centrally located flame spreader, a centrally located 10 mantle support mounted thereon and spaced members for supporting the flame spreader from the upper edge of said sleeve, there being openings formed through the lower portion of said sleeve and there being openings formed through the up-turned portion 15 D of the outer wick tube, said horizontal flange separating the last named openings from the opening of the sleeve.

7. In a device of the character described,

the combination with a bowl, of an inner 20 wick tube and an outer wick tube, a sleeve adapted to surround the upper end of the outer wick tube, there being an out-turned horizontal flange upon the upper end of the outer wick tube, lugs carried by said flange 25 adapted to concentrically space said sleeve from the outer wick tube, there being openings formed through the lower portion of said sleeve, and an imperforate horizontally disposed flange upon which said sleeve is 30 adapted to rest and which closes the bottom of said sleeve.

In testimony whereof, I affix my signature, in presence of two witnesses.

BERNARD F. ROEHRIG.
